UNITED STATES PATENT OFFICE.

ROUGIER THORNE, OF GLEN COVE, NEW YORK.

LANTERN.

1,413,244.

Specification of Letters Patent. Patented Apr. 18, 1922.

Application filed March 4, 1920. Serial No. 363,158.

To all whom it may concern:

Be it known that I, ROUGIER THORNE, a citizen of the United States, and resident of Glen Cove, in the county of Nassau and State of New York, have invented certain new and useful Improvements in Lanterns, of which the following is a specification.

The invention pertains more particularly to lanterns for marine use, and the purposes of my invention are to improve the construction of marine lanterns and to provide therein safeguards against the effects of rain, wind, oscillation, and the movements of a yacht or ship. The lantern of my invention is also equipped with means for adjusting the draft through the same and adjusting the wick from the outside of the lantern, and the parts of the lantern of my invention have been designed with the view of being capable of ready manufacture and of being easily assembled and disassembled. My lantern comprises three main parts in addition to the burner or lamp feature, one of said parts being a base having a door at its bottom and capable of receiving the oil-fount of the lamp, and another of said parts being a superposed structure comprising a chimney, protecting hood, draft apertures, means for regulating the same, and means for baffling the top portion of the lantern against the action of sudden gusts of wind and strong breezes, while the third main part of the lantern resides in the tubular Fresnel lens which, in accordance with my invention, is removable from the lantern, when necessary.

My invention resides in the novel features of construction, arrangement and combination of parts hereinafter described, and particularly pointed out in the claims, and will be understood on reference to the following description taken in connection with the accompanying drawings, in which:

Fig. 1 is a central vertical section through a lantern constructed in accordance with and embodying the invention;

Fig. 2 is a horizontal section through the same taken on the dotted line 2—2 of Fig. 1;

Fig. 3 is a top view taken on the dotted line 3—3 of Fig. 1 of the upper portion of the lantern, with the dome and chimney omitted;

Fig. 4 is a horizontal section through the lantern taken on the dotted line 4—4 of Fig. 1;

Fig. 5 is a vertical section, partly broken

away, of a detailed portion of the base of the lantern, showing an inner slidable door about the wick-operating shaft and being on the dotted line 5—5 of Fig. 1; 60

Fig. 6 is a horizontal section, partly broken away, through the same taken on the dotted line 6—6 of Fig. 5;

Fig. 7 is a bottom view of the lantern;

Fig. 8 is a vertical section through the upper portion of the base of the lantern, and is presented to illustrate the sleeve within which the body of the lamp is held, and

Fig. 9 is a side view of a portion of the base of the lantern and is presented to illustrate the means for locking the bottom of the lantern in closed position.

In the drawings 10 designates the base portion of the lantern, 11 the superstructure thereof, and 12 the tubular Fresnel lens 75 interposed between said portions 10, 11 and removable when desired, as hereinafter explained.

The base portion 10 is in the form of a hollow shallow cylindrical sheet-metal receptacle having vertical sides 13, a hinged bottom 14, and a cap portion 15 which is preferably slightly domed about its outer portions and is perforated, as at 16, within the vertical plane of the walls of the lens 12. 85 At its central portion the top of the base 10 is provided with a central vertical sleeve 17 which is open at its upper and lower ends and extends partly above and partly below the top of the base 10. The sleeve 17 is 90 plain and tubular except at its opposite sides where it is formed with internal grooves 18 which are pressed into the metal of the sleeve and comprise a vertical portion 19, an upper horizontal portion 20, and a portion 21 extending downwardly from the horizontal member 20 of said grooves, as more particularly indicated in Figs. 1 and 8. The purpose of the grooves 18 will be explained hereinafter. Upon the top 15 of the base 10 100 is rigidly secured by riveting or otherwise a circular open-top channel member 22 which affords a seat and retaining means for the lower end of the lens 12, as will be understood on reference to Fig. 1. The bottom 14 100

of the base 10 is hinged at one edge, as at 23, and at the opposite side of the base 10 I provide a lock for securing the bottom 14 in closed position, this lock consisting of a slideable wire rod 24 mounted in sleeves 25 110 formed on the base 10 and adapted at one end to be moved into a sleeve 26 formed

on the bottom 14 so as to secure said bottom in closed position, said rod and sleeve being familiar features in this art. The main body of the bottom 14 is offset upwardly, as shown in Fig. 1, and this portion of the bottom 14 is perforated, and within the recess formed in the lower side of said bottom I mount, on a pivot 27, a rotatable disk 28 having air inlet openings 29, 30, which may be brought more or less into register with the openings 31 provided in the bottom 14 for the ingress of air. The disk 28 provides a means for regulating the draft up through the bottom of the base 10, since the openings 29, 30 therein will be brought into more or less register with the openings 31, as occasion may require, the air inlet to the base 10 being reduced on occasions when there is a strong breeze. The bottom 14 may be provided with feet 32 for supporting the lantern upon a base without closing the air inlets through the bottom 14. The base 10 at one side is equipped with a sliding door 33 (Fig. 5) which lies against the inner side wall of the base and is guided in channels formed by horizontal flanges 34 in an ordinary manner, said flanges affording runways and said door being equipped with a small knob 35 for convenience in operating it. The door 33 at one edge is provided with a notch 36 adapted to pass upon a wick-operating shaft 37, as shown. The wick-operating shaft 37 extends to the exterior of the base 10 and is provided with an operating wheel 38, and by reason of the fact that the shaft 37 does extend outwardly beyond the side of the base 10, I provide said side with a vertical slot 39, as indicated by dotted lines in Fig. 5, and with a branch slot 40 which is horizontal and leads laterally from the upper end of the slot 39 and merges into a short vertical slot or recess 41 which finally affords a seat and lock for the shaft 37.

The lamp is to be inserted upwardly through the bottom of the base 10 when the bottom 14 thereof is opened, and during this insertion of the lamp into the lantern the door 33 will be caused to uncover the slot 39 and permit the shaft 37 to be passed upwardly through said slot and then, on the turning of the lamp, carried along the branch slot 40 and finally be allowed to seat in the recess 41. After the lamp has been introduced to its position the door 33 will be slid toward the shaft 37 and close off the slot 39, as shown in Fig. 5, thereby excluding the passage of air through said slot as well as through the branch slot 40 and recess 41. In the absence of the door 33 considerable air might pass through the slots 39, 40 and recess 41, said slots then being open. I locate the wick-operating wheel 38 at the outside of the base 10 so that the wick of the lamp may be raised or lowered without opening the lantern or removing the lamp therefrom.

The lamp comprises an oil-fount 42, an upwardly extending neck-portion 43 through which the wick 44 passes, a wick tube 45 of ordinary character, and a suitable burner 46. The oil may be poured into the fount 42 through an inlet 47 of ordinary construction. The wick will be raised and lowered by means of the usual wick-wheels secured on a transverse shaft 48 having on its outer end a sprocket-wheel 49 connected by a chain 50 with a sprocket-wheel 51 on the aforesaid shaft 37. The chain 50 extends vertically through a chamber afforded by a sleeve 52 which is offset inwardly from the outer wall of the neck 43, in which position said chain 50 will not interfere with the application of the lamp to the sleeve 17. The chain 50 is confined at the inner side of the sleeve 17, and the sleeve 52 being integral with or secured to the neck 43 will not permit leakage about the inner end of the shaft 37. The chain 50 permits of the operation of the wick-wheels on the shaft 48 from a point below the lens 12 and exterior to the base 10, and this is a feature I desire to accomplish since by reason thereof the wick 44 may be adjusted without opening the bottom of the lantern or removing the lamp.

The neck 43 is provided on its opposite sides with pins or small knobs 53, which are utilized in connection with the grooves 18 in securing the lamp in suspended position within the neck 17. In applying the lamp to position in the lantern the bottom 14 is opened downwardly and the door or shutter 33 is slid from over the slot 39 in the side of the base 10, and thereupon the lamp may be inserted upwardly into the lower end of the lantern, the shaft 37 being moved upwardly through the slot 39 and the knobs 53 on the neck 43 caused to pass upwardly through the grooves 18. When the shaft 37 has reached the upper end of the slot 39 and the knobs or pins 53 have reached the upper end of the vertical portions 19 of the grooves 18, the lamp will be turned angularly so that the shaft 37 may move along the branch groove 40 and finally reach its seat in the recess 41 and so that the knobs or pins 53 may, at the same time, travel along the grooves 20 and become seated in the recesses 21, in which position of the lamp said lamp becomes securely suspended within the sleeve 17, and the recesses 21 of the grooves 18 and 41 of the slots 39 securely hold the lamp against angular or twisting movement. After the lamp has been introduced into the lantern and becomes properly positioned therein, the door or shutter 33 will be moved to its closed position, covering the slot 39, as shown in Fig. 5, and the bottom 14 of the lantern will be closed and locked in its closed position.

The lens 12 is a tubular Fresnel lens, and said lens requires no particular description,

except to say that it is in one piece and tubular and removable, when required, from the lantern, said lens not being a fixture rigidly secured within the lantern parts.

5 The lens 12 may, therefore, be readily cleaned whenever required and replaced by new lenses, whenever that should be necessary. In the usual type of lanterns the lens is rigidly fastened in place and not removable except with considerable difficulty, it not being intended that the lens may be removable. The upper and lower ends of the lens 12 are formed with smooth annular sections 54, 55, respectively, the section 55 re-
10 movably fitting within the channel 22, and the section 54 being within a reasonably close-fitting opening 56 in a locking ring 57, which forms a part of the superstructure of the lantern.

15 The superstructure 11 comprises a domed sheet-metal top 58 having a central upwardly extending tubular chimney portion 59, a base ring 60 to which the top 58 is secured by a hinge 61, the aforesaid locking ring 57 which
20 is supported by said base ring 60, an exterior bell-shaped protector or hood 62 which projects downwardly over the chimney 59, a rotary draft regulator sleeve 63 mounted on said chimney 59, and baffle plates 64, 65, re-
25 spectively, secured to the inner surface of the hood 62 and exterior surface of the chimney 59, respectively. The upper end of the chimney 59 is perforated, as at 66, and the upper end of the sleeve 63 is correspondingly perforated, as at 67, and said sleeve is made rotatable so as to act as a register for cutting off more or less of the area of the perforations 66, as occasion may require. I
30 secure a handle 68 to the sleeve 63 as a convenience for rotating said sleeve. The vertical sides of the hood 62 are spaced outwardly from the sleeve 63 so as to create a commodious passage for the escape of the products of combustion and maintain a proper draft through the lantern, and to prevent a strong breeze or sudden gust of wind from interfering with the correct action of the lantern, I provide the baffle plates 64, 65 in the space between the hood 62 and
35 sleeve 63, the baffle plate 64 extending inwardly from the hood but not touching the sleeve 63, and the baffle plate 65 extending outwardly from the chimney 59 toward but not touching the hood 62. The baffle plates 64, 65 aid in preventing an unduly swift discharge of the heated air and products of combustion from the chimney 59 and also baffle any wind or breeze which might, especially when the lantern is used for marine purposes, otherwise move upwardly into the hood 62 and enter the chimney 59. On the top of the hood 62 I preferably apply a ring handle 69.

40 The domed top 58 is secured at one edge by
45 the hinge 61 to the base ring 60, and hence

said top may be turned upwardly from over the lens 12 whenever necessary. I secure the top 58 in its closed position by means of a suitable locking wire 70 which may be mounted in sleeves 71 secured on the top 58 70 and slideable into a sleeve 72 formed on the base-ring 60. When the wire 70 is slid in one direction the top 58 becomes released to turn upwardly on its hinge 61, and when said top is closed down upon the ring 60 and said wire 70 is slid in the opposite direction, the wire will lock the top 58 in its closed position, a locking wire 70 of a character illustrated being familiar in this art.

45 The base-ring 60 is a flat ring of substantial strength and supported upon the upper ends of the cage wires 73, whose upper ends are fastened to the ring 60 and whose lower ends are secured to the top 15 of the base 10. The ring 60 is formed in its upper surface 80 with an annular depression or recess 74 into which is seated the locking ring 57, said ring 57 being, at its inner edges, extended inwardly beyond the inner edges of the ring 60, as shown in Fig. 1, so that the ring 57 90 may rather snugly engage the upper plain section 54 of the lens 12, said ring 57 being provided for the purpose of holding the upper end of the lens 12 stationary and more especially against vibration. The ring 57 is 95 a flat band of sheet metal and has at certain points in its outer edge recesses 75, as shown in Fig. 3, and these recesses are utilized in connection with small plates 76 secured to the ring 60 for locking the ring 57 in position. In applying the ring 57 upon the base-ring 60 the recesses 75 will be passed downwardly over the plates 76, and said ring 57 will then be turned angularly or given a partial rotation so as to carry said recesses 100 away from the vertical plane of said plates, or to the position in which said recesses are shown in Fig. 3, in which position of the parts the plates 76 will hold the ring 57 down upon the ring 60 but permit, at the 105 proper time, on a reversal of the movement of said ring 57, the withdrawal of the ring 57 from the ring 60 so as to expose the upper end of the lens 12 and permit said lens to be drawn upwardly through the top of the lantern, the top 11 then being in its open position. The locking ring 57 is movable so as to secure and release at appropriate times the lens 12, and I do not limit my invention to any special means for locking the ring 110 115 57 in its operative position, since said ring 57 may be hinged and locked to the ring 60 in the same manner and by means corresponding with the hinge and lock I make use of for securing the top 58 to the ring 60. If 120 the ring 57 should be hinged to the ring 60 it will be opened and closed in the same manner that the top 58 is opened and closed with relation to said ring 60.

125 The details of my lantern have been here- 130

inbefore described, and it is believed that further description of the structural features may not be required. The operation of the lantern will also be understood from the 5 foregoing description. The lantern is constructed of parts which may be readily manufactured and assembled, and the lantern is efficient in use. The drafts through the lantern for the support of combustion may be 10 controlled at will, and means are provided at the upper end of the lantern for excluding strong breezes and gusts of wind. The interior of the lantern may be readily gotten at, since the bottom 14 and top 58 are hinged 15 to their respective supports, and the lens 12 may be removed and replaced at will. The lamp becomes securely fastened in position and the wick 44 may be adjusted from the outside of the lantern. The form of the base 20 10 and oil-fount 42 permit the lantern to be supplied with an adequate quantity of oil.

What I claim as my invention and desire to secure by Letters Patent, is:

1. A lantern composed of a sheet metal base having a displaceable bottom, a removable lamp applied therein, a superstructure comprising a top having an upwardly extending perforated chimney, a hood extending downwardly over and having its sides spaced from said chimney and baffle plates secured within the space between the sides of said hood and chimney, and a tubular lens interposed between said base and said superstructure and enclosing the wick portion of said lamp, said top being displaceable and said lens being removable through the upper portion of the lantern.

2. A lantern composed of a sheet metal base having a displaceable bottom, a removable lamp applied therein, a superstructure comprising a top having an upwardly extended perforated chimney, a hood over said chimney and at its sides spaced therefrom, air-baffling means secured within the space 45 between the sides of said hood and the sides of said chimney and a rotary perforated register sleeve mounted on said chimney for controlling the area of the perforations therein, and a tubular lens interposed between said base and said superstructure and enclosing the wick portion of said lamp, said top being displaceable and said lens being removable through the upper portion of the lantern.

3. A lantern composed of a sheet metal base having a displaceable bottom, a removable lamp applied therein, a superstructure comprising a top having an upwardly extending chimney, a protecting hood over 60 said chimney, a base ring to which said top is hinged and a displaceable lens-locking-ring on said base ring, and a tubular lens enclosing the wick portion of said lamp and at its lower end mounted on said base and 65 at its upper end being confined within the

opening in said locking-ring, said lens being removable through the upper portion of the lantern.

4. A lantern composed of a sheet metal base having a hinged perforated bottom offset upwardly to form a concentric recess therein and a rotary perforated register plate applied within said recess, a removable lamp applied within said base, a superstructure comprising a top having an upwardly extending chimney, and a hood over said chimney, and a tubular lens interposed between said base and said superstructure and removable through the upper portion of the lantern, the top of said base within the outline of said lens being perforated, said base having means for centering and holding the lower edges of said lens, and said superstructure having means for engaging and holding the upper end portion of said lens. 75 80 85

5. A lantern composed of a sheet metal base having a displaceable perforated bottom, a removable lamp applied within said base and having a fount portion and an upwardly extending neck-portion carrying the 90 burner and wick, a superstructure comprising a top having an upwardly extending chimney and a downwardly extending hood over said chimney, and a tubular lens interposed between said base and said superstructure and removable through the upper portion of the lantern, the top of said base being perforated within the outlines of said lens and having a sleeve to engage the neck-portion of said lamp, said sleeve having inverted 100 bayonet grooves in its opposite sides and said neck-portion of the lamp having on its opposite sides pins to be moved through and seat in the upper portions of said grooves for suspending said lamp within the lantern. 105

6. A lantern composed of a sheet metal base having a displaceable bottom and an inverted bayonet slot in its side, a lamp applied within said base, a superstructure comprising a displaceable top having an upwardly extending chimney and a hood over 110 said chimney, and a tubular lens interposed between said base and said superstructure and removable through the upper portion of the lantern, the top of said base being perforated within the outline of said lens and having a vertical sleeve formed in its opposite sides with inverted bayonet grooves, and said lamp having a neck-portion fitting 115 within said sleeve and provided with pins to be moved through and seat in said grooves and a wick-adjusting shaft extending laterally and to the outer side of the said base and so related to said pins that when the lamp is introduced to position said pins will move 120 through the grooves in said sleeve and said shaft will move through said slot in the side of the said base. 125

7. A lantern composed of a sheet metal base having a displaceable bottom and a lens- 130

- receiving concentric channel on its top, a lamp applied within said base, a superstructure comprising a displaceable top having an upwardly extending chimney, a hood thereover and displaceable concentric lens-engaging means, and a tubular lens mounted in said channel on the base and secured at its upper end by said engaging means and enclosing the wick-portion of said lamp, the top of said base being perforated within the outlines of said lens and having a concentric sleeve and said lamp having a fount and a neck-portion fitting within said sleeve, and said sleeve and neck having interlocking means for securing the lamp in position. 8. A lantern composed of a sheet metal base having a displaceable bottom and an inverted bayonet slot in its side, a lamp applied within said base, a superstructure comprising a displaceable top having an upwardly extending chimney, and a tubular lens interposed between said base and said superstructure and removable through the upper portion of the lantern, the top of said base being perforated within the outline of said lens and having a vertical sleeve formed in its opposite sides with inverted bayonet grooves, said lamp having a neck-portion fitting within said sleeve and provided with pins to be moved through and seat in said grooves and a wick-adjusting shaft extending laterally to the outer side of the said base and so related to said pins that when the lamp is introduced to position said pins will move through the grooves in said sleeve and said shaft will move through said slot in the side of the said base, and said base being provided on its side with a slidable shutter for closing the slot therein after said shaft has reached its operative position. 9. A lantern composed of a sheet metal base having a displaceable bottom and a slot in its side, a lamp applied within said base, a superstructure comprising a displaceable top, and a tubular lens interposed between said base and said superstructure and removable through the upper portion of the lantern, the top of said base being perforated within the outline of said lens and having a vertical sleeve, and said lamp having a neck-portion fitting within said sleeve and provided on one side with an inwardly offset chamber, a wick-wheel shaft at the upper end of said neck-portion, an operating shaft at the lower end of said neck-portion and connected by intermediate mechanism with said wick-wheel shaft and extending outwardly to the outside of said base, said intermediate mechanism being within said chamber, said operating shaft being adapted to be moved upwardly through the slot in the side of said base, and said neck-portion and said sleeve having interlocking means for securing the lamp in suspended position in the sleeve. 10. A lantern composed of a hollow metal base portion having a displaceable bottom for admitting and permitting the removal of a lamp through the lower end of said base, a lamp removably applied within said base and extending at the burner above the same, an intermediate rigid structure including the lantern-lens mounted on said base and extending around the burner portion of the lamp, a top over said intermediate structure and having a chimney extending upwardly therefrom and a hood closed at its top and extending downwardly over and having its sides spaced from said chimney, said lamp having wick operating wheels near the burner, an operating shaft extending out through the side of said base below the horizontal plane of said wheels and intermediate motion-transmitting means connecting said operating shaft with the wick-wheel shaft.

Signed at New York city, in the county of New York and State of New York, this 3rd day of March, A. D. 1920.

ROUGIER THORNE.
